UNITED STATES PATENT OFFICE.

WINFIELD W. STEVENSON, JR., OF STEINMAN, VIRGINIA, ASSIGNOR OF ONE-HALF TO
WILEY H. BLEVINS, OF STEINMAN, VIRGINIA.

CHECK HOLDER AND PROTECTOR.

Application filed May 27, 1924. Serial No. 716,101.

This invention relates to devices for holding and protecting miners' checks.

In mining operations, it is necessary to have a means of designating cars, as they are loaded, in order that credit, for the loading, may be given to the miner to whom the credit is due. In order to accomplish this a system has been devised whereby the miner, as he finishes loading a car, may 10 designate the same as containing a load for which he should be given credit.

A miner is furnished with a set of metal checks upon each one of which is impressed his designating number. As he finishes the 15 loading of each car he hangs thereon one of these checks bearing his number. A man known as the "tipple boss" removes these checks from the cars. At the end of each shift, it is the duty of the "tipple boss" to 20 see that credit is given to the miners whose checks were removed, by him, from the cars. Quite frequently these checks become accidentally lost or are intentionally removed and other checks hung in the place 25 of the checks of the miners who actually loaded the cars. These conditions cause considerable dissatisfaction.

An important object of my invention is the provision of a device for holding and 30 protecting the checks so placed upon the cars, in such a manner that the difficulties above mentioned, will be obviated.

Other important objects are to provide a 35 check protector which (1) will permit of the reception and retention of a miner's check, (2) will prevent the insertion of another until the previously inserted check has been removed, (3) will permit of the removal of the check by the "tipple boss" or other 40 designated company officer, (4) will provide a safe locking means to prevent one not having a proper key, from unlocking the check holder and removing the same, (5) will return the parts to their normal and 45 receptive positions when a previously placed check is removed, (6) will be simple, cheap of manufacture, positive in action, easy of operation and practically "fool proof".

Referring to the drawing wherein I have 50 illustrated a preferred embodiment of my invention,

Fig. 1 is a front view of my invention attached to the body of a mine car and showing a portion of the box broken away,

Fig. 2 is a vertical section on the line 55 2-2 of Fig. 1,

Fig. 3 is a view similar to Fig. 1 but showing the check in the box and the parts in position after the check has been inserted,

Fig. 4 is a sectional view on the line 60 4-4 of Fig. 3,

Fig. 5 is a view similar to Figs. 1 and 3 but showing the parts in a position where the check is about to be discharged and the parts returned to normal position in readiness to receive another check,

Fig. 6 is a side view of the lock body detached from the box with the disk 16 in its proper place but without the spring,

Fig. 7 is a detached side view of the lock 70 cylinder with the disk 41 mounted rigid therewith,

Figs. 8 and 9 are plan and elevational views, respectively, of the miner's check.

Similar reference characters refer to the 75 same parts throughout the several views of the drawing,

10 designates the box or receptacle body to which the working parts of my invention are attached. 11 designates the lid or cover 80 of the box to which it is secured in any well known or suitable manner.

In the front of the box is suitably secured, as by threading, a lock body 12. The lock body 12 carries suitable plungers 13 85 which are normally pressed downwardly by the plunger springs 14. On the end of the lock body, farthest from the point of support, is a cylindrical bearing surface 15 upon which is rotatably mounted a flanged 90 disk 16. This disk 16 is provided with a flange 17 and a detent member 18, both integral therewith and extending in opposite directions from the disk.

Pivotedly supported from the wall of the 95 box is a trigger 19 having its pivot 20 in a bracket 21 suitably secured to the wall of the box as by the screws 22. The trigger 19 is provided with a suitable notch 23 and the bracket 21 is mounted to support the 100 trigger 19 in such a position that the notch 23 may engage the detent member 18 of the disk 16.

A coil spring 24 encircles the bearing 105 flange 25 of the disk 16 and has one end secured in an opening 26 in the detent member 18 and the other end secured in an opening 27 in the trigger guide 28. This spring

24 normally tends to turn the disk in a counter-clockwise direction as seen in Fig. 1.

The trigger guide 28 is suitably secured to the box 10 as by the screws 29. This trigger guide is provided with a bifurcated portion having a slot 30 in which the body of the trigger travels. The trigger 19 is provided with a laterally extending arm 31 which extends across and below one end

10 of a slot 32 in the box body 10. The slot 32 is of a size to admit entrance to a check 33, shown in Figs. 8 and 9. A spring 34 is attached at one end to the trigger 19 and at the other to the trigger guide at 35. This

15 spring 34 normally tends to hold the laterally extending arm 31 of the trigger 19 in a position across the slot 32 for a purpose to be later described. It will be observed that the flange 17 of the disk 16 is in the

20 plane of the slot 32 and when the disk rotates to an upper position, the flange forms a closure member for the slot 32. The purpose of the construction will also be later described.

25 A stop 36 is provided and is rigid with the lid or cover 11 of the box. This stop is in position to be engaged by the flange 17 of the disk 16 when it revolves by the power derived from the spring 24.

30 Mounted to revolve in the lock body 12 is a lock cylinder 40. At the outer end of the lock cylinder 40 is a flange 40^a which prevents inward movement of the cylinder. At the inner end of the cylinder 40 is secured a disk 41. The disk 41 and the cylinder

35 40 are secured together by screws 42 and lugs 43, the latter of which coact with corresponding recesses in the cylinder. The length of the bearing for the cylinder in the lock body 12 and its own length are sub-

40 stantially equal so that there is no axial movement of the cylinder in the lock body. The lock cylinder is provided with plungers 44 which are operated by a key and coact with the plungers in the lock body to effect a locking and unlocking of the mechanism in a well known manner. A key hole for the admission of the key is provided at 45.

50 A flange 46 is provided on the disk 41 and a portion of the flange is broken to extend outwardly in the plane of the disk to form the lug 47. It is to be noted, from the side sectional view illustrated in Fig. 2, that the flange 46, as well as the flange 17 is in the plane of a slot or opening 48 in the wall of the box and at its bottom.

55 In the operation of my device as a check holder and protector on mine cars, the box would be secured in position on a car with the slot 32 at the top and the slot 48 at the bottom. After the miner had loaded his car, he would insert his check into the slot 32.

60 I will now describe the operation of the several parts of my invention when a check is inserted in the slot 32. The entrance of

the check causes the trigger to move against the action of the spring 34. As soon as the trigger has moved to a point where the wall of the notch 23 disengages the detent member 18, the spring 24 will cause the disk 16 70 and its flange 17 to revolve. This movement continues until the flange 17 engages the stop 36. The spring 24 holds the disk 16 and its flange 17 in this position.

The disk is now held from passing out of 75 the slot 48 by the flange 46 of the disk 41 and is prevented from being withdrawn by the placement of the flange 17 across the slot 32. Furthermore, no other checks are permitted to enter for the same reason. 80

When the proper person who has the key, such as the "tipple boss," desires to secure the check, he inserts the proper key in the key hole 45. This raises the lock plungers to a point where their upper faces coincide 85 with the upper wall of the cylinder and the lock body plungers which normally prevent movement of the cylinder, are forced into the lock body. A turning movement of the key, in a direction opposite to the direction of movement taken by the disk 16 when the disk entered, now causes the flange 46 to uncover the slot 48. The check then falls out and is preserved. Continued movement of the key and the cylinder, in the same direction, causes the lug 47 to engage the edge of the flange 17. Movement is continued against the force of the spring 24 until the detent member 18 engages the notch 23. The spring 34 now brings the trigger to 100 the left as seen in Fig. 1 and the disk 16 is held. The key is now turned backwardly to bring the cylinder to its original locking position, after which it is withdrawn and the device is ready to receive another check. 105

While I have shown and illustrated a preferred form of my invention in detail, I desire to have it understood that I do not limit myself to the exact details shown and that modifications and changes may be made 110 without departing from the spirit of my invention and within the scope of the appended claims.

Having described my invention, what I claim and desire to secure by Letters Patent, 115 is:—

1. A check holder and protector comprising a receptacle to receive a check, means operated by the insertion of a check to close the receptacle against further check entry, means for supporting the check in the holder and a lock means for removing the supporting means from operative position and permitting the check to fall by gravity through an opening in the holder. 120

2. A check holder and protector comprising a receptacle to receive a check, means operated by the insertion of a check to close the receptacle against further check entry, a lock for unlocking the receptacle and means 125 130

- cooperating with the lock to discharge the check.
3. A check holder and protector comprising a receptacle having a slot to receive a check, means operated by the insertion of a check to close the receptacle against further check entry, a lock for unlocking the receptacle and means cooperating with the lock to discharge the check.
- 10 4. A check holder and protector comprising a receptacle having a slot to receive a check, a closure member for the slot, means under control of the check for operating the closure member after admission of the check, a lock for unlocking the receptacle and means cooperating with the lock to discharge the check.
- 15 5. A check holder and protector comprising a receptacle having a slot to receive a check, a closure member for the slot, means for operating the closure member after admission of the check, a lock for unlocking the receptacle and means cooperating with the lock to discharge the check and place the closure member in non-closed position relative to the slot.
- 20 6. A check holder and protector comprising a receptacle having a slot to receive a check, a spring operated closure member for the slot, means operated by the insertion of the check in the slot to release the closure member to close the slot, a lock means for unlocking the receptacle to release the check.
- 25 7. A check holder and protector comprising a receptacle having a slot to receive a check, a spring operated closure member for the slot, means operated by insertion of the check in the slot to release the closure member to close the slot, a lock for unlocking the receptacle and means cooperating with the lock to release the check and return the closure member to its initial non-closed position.
- 30 8. A check holder and protector comprising a receptacle having a slot to receive the check and an opening for the discharge of the check, a normally inoperative closure member for closing the slot against further check entry and a normally operative closure member for the opening, means operative by the insertion of the check to operate the slot closure member and a lock for unlocking the closure means for the opening to discharge the check.
- 35 9. A check holder and protector comprising a receptacle having a slot to receive the check and an opening for the discharge of the check, a normally inoperative closure member for the slot and a normally operative closure member for the opening, means operative by the insertion of the check to operate the slot closure member, a lock for unlocking the closure member for the opening to discharge the check and means cooperating with the lock to return the slot closure member to its initial non-closing position.
- 40 10. A check holder and protector comprising a receptacle having a slot to receive the check, a normally inoperative pivoted closure member for the slot, means under control of the check to operate the slot closure member, a check supporting member within the receptacle, a lock for removing the supporting member from operative position to discharge the check.
- 45 11. A check holder and protector comprising a receptacle having a slot to receive the check and an opening for the discharge of the check, a normally inoperative pivoted closure member for the slot, means under control of the check to operate the slot closure member, a normally operative pivoted closure member for the opening and lock means for removing the pivoted closure member from operative position to permit the discharge of the check through the opening.
- 50 12. A check holder and protector comprising a receptacle having a slot to receive the check and an opening for the discharge of the check, a normally inoperative pivoted closure member for the slot, means under control of the check to operate the slot closure member, a normally operative pivoted closure member for the opening and locking means for controlling the discharge of the check and for returning the closure members to their respective normal positions.
- 55 13. A check holder and protector comprising a receptacle having a slot to receive the check and an opening for the discharge of the check, a normally inoperative pivoted closure member for the slot, means operative by the insertion of the check to operate the closure member to close the slot against further check entry, a normally operative pivoted closure member for the opening and lock means for removing the closure member from operative position to permit the discharge of the check through the opening.
- 60 14. A check holder and protector comprising a receptacle having a slot to receive the check and an opening for the discharge of the check, a normally inoperative pivoted closure member for the slot, means operative by the insertion of the check to operate the closure member, a normally operative pivoted closure member for the opening and a locking means for controlling the discharge of the check and for returning the closure members to their respective normal positions.
- 65 15. A check holder and protector comprising a receptacle having a slot to receive the check, a normally inoperative closure member for the slot, a pivoted tripping lever having a portion adjacent the slot and in position to be operated by the check when inserted, means coacting with the lever and closure member for operating the latter, to

close the slot, when the former is operated, close the slot when the former is operated, and locking means for unlocking the receptacle to release the check.

16. A check holder and protector comprising a receptacle having a slot to receive the check, and an opening for the discharge of the check, a normally inoperative pivoted closure member for the slot, a pivoted tripping lever having a portion adjacent the slot and in position to be operated by the check when inserted, means coacting with the lever and closure member for operating the latter to
- 15
20

close the slot when the former is operated, a normally operative closure member for the opening, a lock operatively connected to the closure member for the opening for operating the same to open the opening to discharge the check and connections between the lock and closure means for the slot to open the same after the check has been discharged.

In testimony whereof I hereunto affix my signature.

WINFIELD W. STEVENSON, JR.
